DESIGN FOR A GRAVE VAULT

Elisha H. Scott, Richmond, Ind., assignor to W. N.
Johnson Automobile Sheet Metal Works, Rich-
mond, Ind., a corporation of Indiana

Application May 29, 1933. Serial No. 48,240

Term of patent 7 years

To all whom it may concern:

Be it known that I, ELISHA H. SCOTT, a citizen of the United States, residing at Richmond, in the county of Wayne and State of Indiana, have invented a new, original, and ornamental Design for a Grave Vault, of which the following is a specification, reference being had to the accompanying drawing, forming a part thereof.

The accompanying drawing is an isometric perspective of my grave vault design.

The dominant feature of my design resides in the arrangement of a center panel on the top and sides of the vault, intermediate the ends thereof. The panel is characterized by the raised irregular portions, the whole being suggestive of a blanket or flag resting on the vault.

I claim:

The ornamental design for a grave vault substantially as shown and described.

ELISHA H. SCOTT.
